UNITED STATES PATENT OFFICE.

PHILIPP VOGT, OF UTICA, NEW YORK, ASSIGNOR TO CHARLES L. LETSON, OF UTICA,
NEW YORK.

AUTOMATICALLY-OPENING MUSIC RACK.

Application filed December 11, 1923. Serial No. 680,020.

To all whom it may concern:

Be it known that I, PHILIPP VOGT, a citizen of the United States, and a resident of Utica, in the county of Oneida and State of New York, have invented certain new and useful Improvements in Automatically-Opening Music Racks; and I do hereby declare that the following is a full, clear, and exact description thereof, which will enable others skilled in the art to which it appertains to make and use the same, reference being had to the accompanying drawings, and to the reference numerals marked thereon, which form part of this specification.

My present invention relates to a music rack of the folding type and particularly to one which is adapted to automatically unfold or extend itself when released.

The purpose of my invention is to provide a music rack of the folding type which is adapted to automatically unfold or extend itself and further to provide convenient and preferably spring operated means for holding the rack closed when its parts are moved to folded position.

Further purposes are to provide a music rack of the class described which is simple and durable in construction and operation and adapted to be readily opened or closed.

Further purposes of my invention will appear from the specification and claims herein.

Fig. 1 is a plan view of a music rack embodying my invention with the parts in unfolded or extended position and with the parts on one side of the rack shown in dotted lines in partly folded position.

Fig. 2 is a front view of the device on a larger scale when its parts are closed.

Fig. 3 is a side elevation of the device as shown in Fig. 2 as seen from the right hand side.

Fig. 4 is a front view on an enlarged scale of the upper left hand portion of the rack when open but with the ear 38 in line with the side bar 18.

Fig. 5 is a similar view of the rear side of said portion of the rack.

Referring to the drawings in a more particular description it will be seen that the device comprises a central upstanding stem 10 having a pair of oppositely disposed parallel slots 11 and 12 extending from points a little below the upper end of the stem to points a little more than half way towards

the lower end of the stem; a pair of bottom bars 13—13 having a forwardly extending flange 14 and pivoted at spaced points by pivots 15 to the central stem near its lower end, each of said bottom bars having a slot 16 extending from near the outer end of the bar to a point near its inner end; a pair of normally diagonally arranged arms 17 respectively pivoted at their lower ends to the central stem 10 by the pivots 15 already mentioned; two side bars 18 for the outer side of the rack pivoted respectively by pivot pin 19, near the upper ends of said side bars to the upper ends of the arms 17 and two top pieces 20 pivoted at their outer ends by pivot 19 to the outer ends of the arms 17.

The lower end of each of the outer side bars 18 is provided with a pin 21 whereby the lower end of each side bar is pivotally and slidably connected to the bottom bar on its side of the rack by said headed pin 21 projecting through the slot 16 on said bottom bar. Similarly the inner end of each of the top pieces 20 is provided with a headed pin 22 slidably mounted in the slot 11 or 12 of the central stem 10.

It will now be seen that the music rack so far described may be folded by the members of the opposite sides of said stem being brought towards said stem and over-lapping it either to the front or the back as herein-after described. This is done by pushing down the inner end of the top pieces 20 so that the headed pins 22 will ride down through the slots on said stem and separately or at the same time pushing inwardly upon the edge bars 18 so that the headed pins 21 will ride inwardly along the slot 16 of the bottom bars. During these operations the arms 17 will approach and finally overlap this half of the central piece and the bottom bar will approach and finally overlap its half of the central stem.

Fig. 1 shows the parts on the right hand half of the rack in partly folded position.

In order, however, to aid and expedite the unfolding of the rack and particularly to hold the rack in extended position until the user wishes to fold the rack again there are provided springs 23 and 24 on each half of the rack. The spring 23 consists of a looped or coiled spring having one or more loops about the pivot 19 and disposed between the edge piece 18 and the diagonal arms 17.

therebelow with the opposite ends 23^b and 23^a of the spring extending along the side piece 18 and the arms 17 respectively and held to said members of the rack as by pins 25 and 26 respectively. The construction, arrangement and tension of the spring is such as to tend to force the extended ends of the spring apart and so tend to force the side piece 18 and arms 17 apart. Similarly 10 there is arranged between the diagonal arm and its subjacent top piece 20 the spring 24 having oppositely extended ends 24^a and 24^b and held to said members 17 and 20 by pins 27 and 28 so as to tend to force the top piece 15 20 and the diagonal arms 17 apart.

Close to the upper end of the central stem 10 there is provided a pin 29 projecting from both front and rear surfaces of said stem. The portion at the front serves as a stop to 20 engage the normally diagonally arranged arms 17 when they are folded to overlap said stem, said stop serving to prevent either arm being swung past the center of said stem. Similarly the portion of said pin 29 at the 25 back engages the top pieces 20 and prevents their being swung past center. As the arm and top piece on each side of the rack are pivoted together at their upper ends a stop operating either against the arm or the top piece would be sufficient; but I prefer to have the stop operate against both parts.

A little ways down from the top of one side bar 18, say the right hand bar, there is provided a finger 30 extending towards 35 the center of the rack, having a downwardly extending hook 31. Preferably this finger is at the back of said bar 18, as shown in the drawings. Upon the back of the other side bar 18, is provided a co-operating catch 40 member or plate 32, mounted to slide a short distance longitudinally of said bar 18 as by an elongated rivet 33 moving in a slot in said bar. The front of said rivet is secured to a finger piece 34, lying flat 45 upon the front surface of the bar 18. The top of the plate 32 has an upstanding shoulder 35, adapted to engage the hook 31 of the finger 30 when both halves of the music rack are in folded position. This 50 member of the catch is spring tensioned so as to be forced upward upon the bar by means of a looped spring 36. The upper edge of the plate 32 has a sloping edge 37 co-operating with the forward and lower 55 edge of the finger 30 to form a cam face so that the downward pressure of the finger 30 upon the cam face 37 when the two members of the catch are brought together temporarily depresses the plate 32 against the 60 tension of spring 36 until the hook 31 passes the cam face 37. Then the plate 32 is again forced up by the springs 36 and the shoulder 35 engages the finger 31. The details of 65 these parts are shown in Figs. 4 and 5. To release the rack from folded position, the

user temporarily slides the finger piece 34 downwardly and thereupon the springs 23 and 24 force the rack apart.

Upon each side bar 18 there are pivotally mounted ears 38 by means of rivets 39. To the upper ends of each of these ears is swingingly secured a spring wire 40. These spring wires may be used as page holders for the book or leaflet of music upon the rack. When a very wide book is being used one or both of the ears 38 may be swung outwardly as shown in Fig. 1 in order to give greater width between the page holders 40. As shown in Fig. 4 a pin 41 may be mounted upon the bar 18 a little distance from the pivot 39 to engage shoulders 42 and 43 upon the ear 38 at the opposite extremes of desired motion of said ear.

A socket 44 secured to the rear side of the stem 10 affords means for detachably 85 securing this music rack to the top of any suitable upright after the usual manner.

What I claim as new and desire to secure by Letters Patent is:

1. In an automatically-opening music rack, the combination of a central stem with longitudinally extending spaced slots, two oppositely disposed flanged bottom bars pivotally connected at their inner ends to the bottom of the central stem and each having a slot extending from near its outer end nearly to its inner end, two oppositely disposed diagonally arranged arms pivoted at their lower ends to the bottom of the central stem, two side bars each having its upper end pivoted to the upper end of one of the arms and with its lower end having a headed pin pivotally and slidably mounted in the slot of one of the bottom bars, two top pieces, each pivoted at its outer end to the upper end of one of the arms and with its inner end having a headed pin pivotally and slidably mounted in one of the slots in the stem, springs attached to the top piece, to the diagonal arm and to the side bar on each side adjacent the connecting ends thereof and adapted to move the parts to extended position and yieldingly hold them in such extended position against the tension of said springs and means on the rack members for holding the rack in folded position.

2. In an automatically-opening music rack, the combination of a central stem with longitudinally extending spaced slots, two oppositely disposed, flanged bottom bars pivotally connected at their inner ends to the bottom of the central stem and each having a slot extending from near its outer end nearly to its inner end, two oppositely disposed diagonally arranged arms pivoted at their lower ends to the bottom of the central stem, two side bars each having its upper end pivoted to the upper end of one of the arms and with its lower end having

a headed pin pivotally and slidingly mounted in the slot of one of the bottom bars, two top pieces, each pivoted at its outer end to the upper end of one of the arms and 5 with its inner end having a headed pin pivotally and slidingly mounted in one of the slots in the stem, springs operatively connected to the top piece, diagonal arm and side bar on each side and adapted to 10 move the parts to extended position and yieldingly hold them in such extended position and a spring catch having its members on opposite sides of the rack for holding the rack in folded position.

15 3. In a music rack, the combination of a main frame having edge members, ears pivotally secured to said edge members and

adapted to be housed thereon or extended there-beyond and spring leaf-holders secured to said ears and adapted to operate 20 either from the folded position of said ears or from the extended position thereof.

4. In a music rack, the combination of a main frame having edge members, ears pivotally secured to said edge members and 25 adapted to be housed thereon or extended there-beyond and spring leaf-holders pivotally secured to said ears and adapted to swing to engage the leaf either from the folded position of said ears or from the 30 extended position thereof.

In witness whereof I have affixed my signature, this 12th day of November, 1923.

PHILIPP VOGT.
